COMBINED CIGARETTE HOLDER AND ASHTRAY OR SIMILAR ARTICLE

Paul E. Allen, 13405 SE. Bush St.,
Portland, Oreg. 97236

Filed July 16, 1971, Ser. No. 163,560

Term of patent 14 years

Int. Cl. D27—03

U.S. Cl. D85—2 H

FIG. 1

FIG. 2

FIG. 1 is a perspective view of a combined cigarette holder and ashtray or similar article, showing my new design;

FIG. 2 is an end elevational view; and
FIG. 3 is a bottom plan view thereof.

I claim:

The ornamental design for a combined cigarette holder and ashtray or similar article, as shown.
